(57) **CLAIM**

The ornamental design for a surface mounting light for a vehicle, as shown and described.

DESCRIPTION

FIG. 1 is an isometric view of a surface mounting light for a vehicle, shown in use;

FIG. 2 is an isometric view thereof;

FIG. 3 is a front elevation view thereof, the rear elevation view being a mirror image thereof;

FIG. 4 is a left side elevation view thereof, the right side elevation view being a mirror image thereof;

FIG. 5 is a top plan view thereof; and,

FIG. 6 is a bottom plan view thereof.

The broken lines shown in the drawings illustrate portions of the surface mounting light for a vehicle that form no part of the claimed design.

The cutaway symbols illustrated in break lines in the drawings indicate a symbolic break in the length of the design for the surface mounting light for a vehicle indicating an indeterminate length. The appearance of any portion of the article between the break lines forms no part of the claimed design.
